UNITED STATES PATENT OFFICE

159,508

DOUGHNUT MACHINE

Theodore Morgan, Los Angeles, Calif.

Application June 13, 1949, Serial No. 3,246

Term of patent 14 years

(Cl. D81—10)

To all whom it may concern:

Be it known that I, Theodore Morgan, a citizen of the United States residing at Los Angeles, in the county of Los Angeles and State of California, have invented a new, original, and ornamental Design for a Doughnut Machine, of which the following is a specification, reference being had to the accompanying drawings, forming part thereof.

Figure 1 is a perspective view of a doughnut machine, showing my new design.

Figure 2 is a plan view of the doughnut machine of Figure 1.

Figure 3 is a rear view.

Figure 4 is a view in side elevation thereof taken from the right of Figure 2.

I claim:

The ornamental design for a doughnut machine, substantially as shown.

THEODORE MORGAN.
